UNITED STATES PATENT OFFICE.

HERMAN WEBER, OF OAK PARK, ILLINOIS.

DAMPENING-MACHINE.

1,283,381.

Specification of Letters Patent. Patented Oct. 29, 1918.

Application filed June 9, 1917. Serial No. 173,880.

To all whom it may concern:

Be it known that I, HERMAN WEBER, a citizen of the United States, and a resident of the city of Oak Park, county of Cook, and 5 State of Illinois, have invented certain new and useful Improvements in Dampening-Machines, of which the following is a specification.

My invention relates to an apparatus and 10 process for dampening collars and other articles in laundries, preparatory to ironing of the same.

The object of my invention is the production of a machine and process through the 15 medium of which a large number of articles may be readily and uniformly dampened, each article being subjected to the dampening process for the same period of time. A further object is the production of a machine and 20 process as mentioned which will be capable of ready operation and which will be highly efficient. Other objects will appear hereinafter.

The invention consists in the combinations 25 and arrangements of parts hereinafter described and claimed.

The invention will be best understood by reference to the accompanying drawings forming a part of this specification, and in 30 which,

Figure 1 is a side elevation of a dampening machine embodying the invention,

Figs. 2 and 3, enlarged sections taken on substantially lines 2—2 and 3—3 respectively of Fig. 1, and

Fig. 4, a partially sectional rear elevation of the machine.

The preferred form of construction as illustrated in the drawings, comprises a base 40 5 from which arises a suitable supporting framework consisting primarily of two spaced vertical struts 6. Extending between the struts 6 is a central roller 7 and vertically spaced from said roller 7 are upper and 45 lower rollers 8 and 9 respectively. Said rollers are interchangeable one with the other and in order to permit of ready detachment or interchanging, each roller is supported at one end in a bearing 10 which is pivotally mounted upon the corresponding strut 6, said bearing being releasably locked in operative position by a bolt or fastening device 11. Upon unloosening of the bolt 11 cooperating with any of said rollers, the roller 50 55 may be rocked to a position corresponding

with the dotted line position of roller 8 in Fig. 4 which of course permits of ready sliding of the same from engagement with the bearing 10. The opposite end of each roller 8 is detachably connected with a stub 60 shaft 12 mounted in a bearing 13, the inner end of said shaft being in slot and tongue connection with the adjacent end of the roller, as clearly seen at the roller 8 in Fig. 4. A shiftably mounted sleeve 14 coöperates with the hub of each roller to hold the same in operative relation with the corresponding shaft 12. When it is desired to unlock any roller from its corresponding shaft 12, it is only necessary to shift the 65 sleeve 14 to the left, as will be readily understood. When this is done, the corresponding end of the roller may be dropped to the position corresponding to the dotted line position of roller 8 in Fig. 4. 70 75

Spined to the outer end of the shafts 12 coöperating with rollers 7, 8 and 9 are friction disks 15, 16 and 17 respectively, and co-operating with said friction disks are friction wheels 18, 19 and 20 respectively which 80 are shiftably mounted upon and spined to a shaft 21. Coöperating with each of the disks 15, 16 and 17 is a collar or sleeve 22 which is threaded upon the corresponding bearing 13, the arrangement being such that 85 any one of said friction disks may be adjusted toward or from the corresponding friction wheel through rotative adjustment of the collar 22 coöperating with said friction disk, the outer end of the collar merely 90 abutting against the adjacent end of the hub of the disk. If desired, ball bearings may be inserted between the adjacent end of each collar and its corresponding disk, as seen in Fig. 4 to alleviate friction. Each collar may 95 be provided with slots to permit of engagement therewith of a spanner wrench or the like for adjusting the same. With this arrangement, it will be seen that each friction disk may be entirely disconnected from its 100 coöperating friction wheel or the frictional engagement between the two adjusted as desired. The shaft 21 is driven through the medium of a bevel gear 23 fixed thereto which meshes with a bevel gear 24 fixed to 105 the shaft 25 mounted in suitable bearings, said shaft 25 carrying pulleys 26 whereby the same may be connected with suitable driving means.

Longitudinal shifting of the friction 110

wheels 18, 19 and 20 in order to control the speed of rotation of the rollers 7, 8 and 9 and the direction of rotation of the same, is effected by means of shifting forks 27, 30 5 and 30' respectively, the shifting fork 27 being slidably mounted upon a supporting bar 28 to which the same may be secured by a set screw 29. Likewise the shifting forks 30 and 30' are mounted upon a supporting bar 10 31 to which said forks may be locked by set screws 32.

Projecting forwardly from the struts 6 and pivotally connected therewith are two supplemental supporting frames 33 and 33', 15 said frames being adjustably connected together by means of screws 34 which are pivotally connected at their lower ends with the frame 33', the upper end of each screw being in swiveled connection with an upper 20 screwed portion 35 which passes loosely through perforated lugs 36 formed upon the upper frame as seen in Fig. 3. Upon the member 35 is threaded a nut 37 which is arranged between the lugs 36. The nuts 37 25 are provided with peripheral sockets or recesses for a spanner wrench or pointed tool whereby the same may be adjusted in order to effect adjustment of the distance between the frames 33 and 33', as will be readily understood. The lower frame 33' is adjustably 30 connected with the main frame by brace bars 38, said brace bars having a plurality of spaced perforations in order to permit of vertical adjustment of the auxiliary frames, 35 as will be readily understood.

Carried at the outer ends of the frames 33 and 33' are guide rollers 39 and 39' respectively which are mounted in bearing members 40 and 40' adjustably secured to 40 said frames. The ends of said rollers are mounted in outwardly opening slots or notches in the members 40, pivotally mounted bolts 41 and 41' respectively being provided to lock said rollers 39 and 39' in engagement with said slots.

With the machine thus constructed, are employed two elongated flexible aprons 42 of uniform dimensions, and which are adapted to be wound upon the rollers 7, 8 50 and 9 either separately or together with the articles to be dampened positioned between the same.

In operating the machine, the aprons 42 are first moistened to the extent desired and 55 then said aprons are wound separately upon the rollers 8 and 9. This having been done, the two outer ends of said aprons are brought forwardly around the guide rollers 39 and 39' and then rearwardly together and 60 suitably secured to the roller 7. The power being connected, the parts will be so adjusted that the roller 7 will be rotated to wind the aprons thereon with the latter arranged together. The friction wheels 19 and 65 20 will be adjusted relative to the friction

disks 16 and 17 to retard the rollers 8 and 9 in order to take up any slack in said aprons as the same are unwound from said rollers and wound upon the roller 7. The operator or feeder will stand in front of the rollers 70 39 and 39' and place the collars or other articles to be dampened successively between the aprons as the latter pass around said rollers 39 and 39', as will be readily understood. 75

When the aprons, with the articles to be dampened arranged between the same, have thus been completely unwound from the rollers 8 and 9 and wound upon the roller 7, the latter will be detached from its mounting and interchanged with either of the rollers 8 or 9. This having been done, the two outer ends of the aprons will be carried together forwardly over one of the rollers 39 and 39' and the same rewound together upon 85 the central roller. This is done to bring the ends of the aprons which were first wrapped upon the roller 7 to the outer side of the roll or coil formed by the aprons. With the aprons thus rewound upon the 90 central roller, the outer ends of the aprons are carried forwardly around the rollers 39 and 39' and thence to the upper and lower rollers to which said ends are fastened. The power is then applied to effect winding of 95 the aprons separately upon the rollers 8 and 9 and the friction wheel 18 so adjusted as to retard rotation of the central roller in order to take up any slack in the unwinding of the aprons therefrom. In this separation and 100 unwinding of the aprons from the central roller, the articles carried between said aprons will be discharged therefrom, as will be readily understood. Through the first re-winding of the aprons, as above described 105 whereby the first ends wrapped upon the central roller will be brought to the outer side of the roll or coil, the articles first inserted between the aprons will be first to be removed, and those last inserted will be the 110 last to be removed, thus resulting in a uniform dampening of all of the articles, which is highly desirable. Without this reverse winding of the aprons as mentioned, it will of course be apparent that the articles first 115 inserted between the aprons will be last to be removed and those last inserted will be first to be removed, the result, with the latter arrangement being that the articles first inserted will be dampened too much and 120 those last inserted will not be dampened enough. This non-uniform dampening is, as above described, eliminated with the construction and process set forth. 125

The machine may be arranged adjacent 125 the ironing machine or mangle of the laundry wherein the same is used, so that the collars or articles dampened, as the same emerge from between the aprons 42 will pass directly into the ironer or mangle. As seen 13

in Fig. 1, rollers 43 are shown diagrammatically illustrating an ironer or mangle. Through the adjustable supporting of the frames 33 and 33', the latter may be vertically adjusted in order to position the rollers 39 and 39' in horizontal alinement with the entrance rollers of the ironer or mangle in connection with which the dampener may be employed. Where the dampener is used in connection with an ironer or mangle, the entrance rollers of the latter will be rotated at a rate of speed such that the peripheries thereof will travel slightly faster than the aprons 42, with the result that the articles in passing from one machine to the other, will be stretched to remove wrinkles therefrom, as is customary before the ironing of dampened collars or similar articles.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A dampener comprising a pair of elongated flexible aprons adapted to be wound together with the articles to be dampened positioned between the same; means for rewinding said aprons; and means for subsequently separating said aprons and winding the same separately, substantially as described.

2. A dampener comprising a pair of elongated flexible aprons between which the articles to be dampened are adapted to be placed; and a plurality of rollers upon which said aprons are adapted to be wound either separately or together with the articles to be dampened positioned between the same, substantially as described.

3. A dampener comprising a pair of elongated flexible aprons between which the articles to be dampened are adapted to be placed; a plurality of rollers upon which said aprons are adapted to be wound; driving means; and means for releasably connecting said rollers with said driving means, substantially as described.

4. A dampener comprising a pair of elongated flexible aprons between which the articles to be dampened are adapted to be placed; a plurality of rollers upon which said aprons are adapted to be wound; driving means; means for releasably connecting said rollers with said driving means; and means for retarding rotation of any of said rollers, substantially as described.

5. A dampener comprising a pair of elongated

flexible aprons between which the articles to be dampened are adapted to be placed; a plurality of rollers upon which said aprons are adapted to be wound; driving means; means for releasably connecting 70 said rollers with said driving means; and frictional means for retarding rotation of any of said rollers, substantially as described.

6. A dampener comprising a pair of elongated flexible aprons between which the articles to be dampened are adapted to be placed; a plurality of rollers upon which said aprons are adapted to be wound either separately or together; and means for driving 80 said rollers at variable speeds, substantially as described.

7. A dampener comprising a pair of elongated flexible aprons between which the articles to be dampened are adapted to be placed; a central roller and two additional rollers arranged one on each side of said central roller upon which said aprons are adapted to be wound either separately or together; and means around which said aprons 90 are adapted to pass in the passage thereof between said central roller and said additional rollers, substantially as described.

8. A dampener comprising a pair of elongated flexible aprons between which the articles to be dampened are adapted to be placed; a central roller and two additional rollers arranged one on each side of said central roller upon which said aprons are adapted to be wound either separately or together; and a pair of spaced guide rollers around which said aprons are adapted to pass in the passage thereof between said central roller and said additional rollers, substantially as described.

9. A dampener comprising a pair of elongated flexible aprons between which the articles to be dampened are adapted to be placed; a central roller and two additional rollers arranged one above and one below 100 said central roller upon which said aprons are adapted to be wound either separately or together; and a pair of adjacently positioned guide elements arranged substantially horizontally coplanar with and spaced 110 from said central roller around which said aprons are adapted to pass in the passage thereof between said central roller and said additional rollers, substantially as described.

10. A dampener comprising a pair of elongated flexible aprons between which the articles to be dampened are adapted to be placed; a central roller and two additional rollers arranged one above and one below 120 said central roller upon which said aprons are adapted to be wound either separately or together; a pair of adjacently positioned guide elements arranged substantially horizontally coplanar with and spaced from said central roller around which said aprons are 130

adapted to pass in the passage thereof between said central roller and said additional rollers; and means for driving said rollers in either direction, substantially as described.

11. A dampener comprising a pair of elongated flexible aprons adapted to be wound together with the articles to be dampened positioned between the same; means for 10 winding said aprons; means for subsequently separating said aprons and winding the same separately; and a pair of guide members adapted to receive the articles discharged from between said aprons upon separation and separate winding of said aprons, substantially as described.

12. A dampener comprising a pair of elongated flexible aprons adapted to be wound together with the articles to be dampened 20 positioned between the same; means for rewinding said aprons; means for subsequently separating said aprons and winding the same separately; and a pair of rollers adapted to receive the articles discharged 25 from between said aprons upon separation and separate winding of said aprons, said rollers rotating at a rate of speed such that the peripheries thereof travel a little faster than the speed of travel of said aprons, substantially as described.

13. A dampener comprising a pair of elongated flexible aprons between which the articles to be dampened are adapted to be placed; and a plurality of interchangeable 35 rollers upon which said aprons are adapted to be wound either separately or together

with the articles to be dampened positioned between the same, substantially as described.

14. The process of dampening articles preparatory to ironing of the same, which 40 consists in winding two damp aprons together and successively inserting the articles between said aprons during the winding of the same together, in then reversely winding said aprons, with said aprons arranged together and said articles positioned between the same, and then unwinding said aprons and successively removing the articles from between the same as the aprons are unwound, substantially as described. 50

15. The process of dampening articles preparatory to ironing of the same, which consists in winding two damp aprons together and successively inserting the articles between said aprons during the winding of 55 the same together, in then reversely winding said aprons, with said aprons arranged together and said articles positioned between the same; then unwinding and separating said aprons and successively removing the 60 articles from between the same as said aprons are unwound and separated; and then mechanically stretching the articles as the same are removed from between said aprons, substantially as described. 65

In testimony whereof I have signed my name to this specification in the presence of two subscribing witnesses.

HERMAN WEBER.
